APPARATUS FOR TREATING SHEET MATERIAL

George C. Borden, Jr., Riegelsville, Pa., assignor to Riegel Paper Corporation, Riegelsville, N. J., a corporation of New Jersey

Application October 20, 1934, Serial No. 749,142

17 Claims. (Cl. 91—18)

This invention relates primarily to sheet material, paper for example, which is coated with a solution of nitrocellulose or other suitable film-forming material and a crystallizable compound dissolved in a common vaporizable solvent, with or without the addition of a coloring agent, and when coated is treated first to evaporate the solvent, set the coating and form the crystals therein and then, by heat, solvents, or otherwise, to remove, or largely remove, the crystals so formed to thereby convert the coating into an ornamental surfacing film having a crystalline configured intaglio; and the specific object thereof is to provide apparatus for conveniently, cheaply, and effectively dissolving and washing out the crystals so formed in such an ornamental surface coating or film.

A so-called coating tower has heretofore been developed and used for applying and treating the coatings, of various kinds, applied for one purpose or another to sheet material, the tower being divided by a central partition into two flues or vertical chambers both of which are suitably heated and through which the sheet as coated is continuously carried, first within one chamber to the top of the tower and thence over the upper end of the partition and down through the other chamber to the bottom thereof.

My new apparatus, which although capable of other uses and in other connections can be conveniently associated with the top of a coating tower such as that briefly described, consists, essentially, of a wash-pan preferably divided into a plurality of compartments, through which the sheet, after the coating has set and the crystals have formed therein, is carried in contact with and washed by a body of a suitable crystal solvent moving therethrough in counter-current to the travel of the sheet and progressively heated to a higher and higher temperature, and it preferably comprises, as subsidiary features, means for continuously removing from the used solvent the crystalline material held in solution therein and returning the recovered solvent to the wash-pan for further use, means for spraying the sheet after it has been washed with the solvent flowing through the wash-pan with fresh solvent, and means for at least partially drying and deodorizing the sheet after it has been so sprayed.

The invention will be understood by reference to the accompanying drawing, in which—

Figure 1 is a diagrammatic view illustrating partly in elevation and partly in section, one

practical and what I now consider to be the best embodiment of my new washing apparatus as associated with a conventional coating tower; and Fig. 2 is an enlarged view of the wash-pan, showing the same in vertical longitudinal section. 5

Referring to the drawing, 1 indicates the coating tower, and 2 indicates the sheet of paper or other material which, as usual, is drawn from a reel 3 over a carrying roll 4, coating roll 5 and carrying roll 6, and thence up through one chamber and down through the other chamber of the tower and over a carrying roll 7, pull rolls 8 and 9, and carrying roll 10 to a wind-up reel 11.

Instead, however, of being carried over the upper end of the central partition on a carrying roll or rolls mounted immediately below the closed top of the tower, the sheet on reaching the top of the tower is passed through a suitable slot in its top covering and carried over a head roll 12 and a carrying roll 13 to and through my new washing apparatus and thence over carrying rolls 14, 15 and 16 back to the second or down chamber of the tower through a second slot in the top covering. 15 20 25

This supplementary apparatus, which is suitably mounted in position adjacent the upper end of the tower, either upon the tower itself or otherwise as may be found most convenient, comprises the wash-pan 17 and a domed cover 17^a therefor. The wash-pan, of the same width as the tower or at least of a width to accommodate the sheet to be treated, is divided into a plurality of compartments 18, 19, and 20 by transverse double-walled partitions 21 and 22 which are of progressively increasing height so that the wash solvent after entering and filling the outer compartment 20 will overflow therefrom into the adjoining compartment 19 and after filling the same will overflow therefrom into the inner compartment 18; and between the double walls of these partitions are mounted heating coils 23 and 24 which are supplied with steam in any suitable manner (not shown) and are adapted to heat the solvent in compartment 20 to a temperature of 110° F., for example, and to further heat it some 20°, or say to a temperature of 130° F., before it leaves compartment 18. The coated sheet material after leaving the carrying roll 13 is passed through a suitable slot in the cover 17^a and thence is carried downwardly and upwardly 30 35 40 45 through the successive compartments of the wash-pan over carrying rolls 25, 26, 27, 28, and 29 which are respectively journaled at each end in hanger bars 30, 31, 32, 33, and 34 (only one of each shown) fixed at their upper ends to the 50 55

- lip of the cover and an angle iron 35 with which this lip is framed. From the carrying roll 29 the sheet is drawn up to the upper part of compartment 20 and thence past and in engagement with 5 first a pair of wiping bars 36 and 37 and then a pair of wiping rolls 38 and 39 all supported at their ends in plates 40 (only one shown) also attached to the lip of the cover and its framing angle iron, the rolls 38 and 39 being preferably 10 connected at one end by gears 41, 42 (shown only in dotted lines) and power-driven in any suitable manner (not shown).

The fluid solvent—a solvent which will dissolve the crystals formed in, but will not materially 15 affect the lacquer base of, the coating film—is delivered to the apparatus from a supply tank 43, provided with supply and overflow pipes 44 and 45, by a pump 46 through pipe 47 and two headers 48 and 49 which extend transversely across 20 the wash-pan over compartment 20 and are respectively equipped with spray nozzles 50 and 51 arranged to deliver the solvent in a spray against the opposite sides of the sheet shortly before these sides engage the wiping rolls 38 and 39 respectively. The solvent so supplied successively 25 fills and then flows through the compartments 20, 19, and 18 and, after being progressively heated and washing the coated sheet travelling therethrough in the opposite direction, is discharged 30 from the wash-pan through an overflow or outlet port 52 located in its inner wall immediately below the top of the adjacent partition; and, for the recovery both of the solvent and of the material of the crystals held in solution therein, 35 the hot and now saturated solution is conducted from the outlet port of the wash-pan by a pipe 53 to the uppermost of a series of connected cooling pans 54, of the usual or any suitable type, in which the crystalline matter held in solution is precipitated out in crystals and removed for further 40 use, and from the lowermost pan the recovered solvent is drawn through the pipe 55 to the intake of a pump 56 by which it is forced through the pipe 57 and inlet port 58 into the upper part 45 of compartment 20, to recirculate through the wash-pan. Suitably stoppered drain outlets 59, 60 and 61 are provided in the bottoms of the respective compartments by means of which the wash-pan may be emptied whenever required.

50 The apparatus, as shown is further provided with a drying chamber 62, suitably mounted above the wash-pan, through which the coated and now solvent-washed sheet 2 is conducted after passing through a slot in the domed cover 17 55 and from which the sheet is returned to the second or down chamber of the coating tower over the previously mentioned carrying rolls 14, 15 and 16. An exhaust fan or blower 63, mounted as upon a platform at the back of the tower and 60 suitably driven (by means not shown), draws hot air from one of the compartments of the tower through a duct 64 (indicated in dotted lines) and forces it through a pipe 65 to a pair of transverse headers 66 and 67 provided with perforations through which the air is blown against the 65 opposite side of the sheet, the hot air and fumes being exhausted by the fan from the top of the chamber through a duct 68.

The operation of the apparatus, which will be 70 obvious from the explanations already given, may be briefly recapitulated as follows: The sheet, a sheet of paper for instance, is drawn from a reel and as it passes over the coating roll 5 is coated with a lacquer solution containing, for example, a 75 nitrocellulose base and phthalic anhydride as

crystallizable material. The paper so coated then passes upwardly through one chamber of the tower which is steam-heated to the required temperature so that when the paper reaches the head roll 12 the solvent of the solution has been evaporated, the coating dried and the crystals formed therein. The paper is then carried down and up through the successive compartments of the wash-pan and in its travel is continuously washed by the fluid solvent, toluol for instance (preliminarily supplied from the tank through the spray nozzles and thereafter supplied both with fresh solvent through the spray nozzles and with recovered solvent through the inlet port 58), which flows through the compartments of the wash-pan in counter-current to the travel of the paper and is progressively heated to thereby progressively increase its capacity to dissolve and hold in solution the material of the crystals formed in the coating film of the paper. After being so washed in the solvent, the paper is directed to the upper part of compartment 20 where it is wiped on its opposite sides by the wiper bars and then is sprayed with fresh solvent and re-wiped by the wiper-rolls first on one side and then on the other. And, finally, the washed sprayed and wiped paper is conducted from the wash-pan to and through the drying chamber, in which it is dried and deodorized to a certain extent, and thence is returned to the other chamber of the tower where it is humidified and further heated, to further deodorize it, and is then reeled up.

It will, of course, be understood, that my new washing apparatus may be used in other connections and for other purposes, and that the several parts thereof may be variously modified in their structural details, or certain parts thereof be omitted entirely, within the scope of the appended claims, without departing from the spirit or sacrificing the substantial advantages of the invention.

What I claim as new, and desire to secure by Letters Patent, is—

1. In apparatus of the type described, the combination, with means for coating a continuous sheet with a solution containing a base material and a crystallizable material, of a heated tower divided into up and down flues through which the coated sheet is carried, an enclosed wash-pan 45 associated with the top of the tower, means for diverting the coated sheet from the upper end of the up flue of the tower and passing it into and through the wash-pan and then returning it to the upper end of the down flue of the tower, means for continuously circulating a body of fluid crystal solvent through the wash-pan in contact with the coated sheet and in counter-current to the direction of its travel, and means for progressively heating the body of solvent as it circulates through the wash-pan.

2. Apparatus according to claim 1, having included therewith means for wiping the coated sheet on leaving the circulating body of fluid crystal solvent.

3. Apparatus according to claim 1, having included therewith means for spraying with additional fluid crystal solvent and means for wiping the coated sheet on leaving the circulating body of fluid crystal solvent.

4. Apparatus according to claim 1, having included therewith a heated chamber through which the coated sheet is passed on leaving the wash-pan and before being returned to the down flue of the tower and which is provided with

- means for exhausting hot air and fumes therefrom.
5. Apparatus according to claim 1, in which the wash-pan is divided from inner to outer end into a plurality of transverse compartments by double-walled partitions closed at the top and of progressively greater height and the means for progressively heating the body of crystal solvent as it circulates therethrough are located between the walls of the partitions.
6. Apparatus according to claim 1, in which the wash-pan is divided from inner to outer end into a plurality of transverse compartments by double-walled partitions closed at the top and of progressively greater height and the means for progressively heating the body of crystal solvent as it circulates therethrough are located between the walls of the partitions and in which there are included means for continuously withdrawing the used crystal solvent from the inner end of the wash-pan, treating it to separate out the crystalline matter held in solution therein, and return the recovered solvent to the outer end of the wash-pan for recirculation therethrough.
7. Apparatus according to claim 1, in which the wash-pan is divided from inner to outer end into a plurality of transverse compartments by double-walled partitions closed at the top and of progressively greater height and the means for progressively heating the body of crystal solvent as it circulates therethrough are located between the walls of the partitions, and in which there are included both means for continuously withdrawing the used crystal solvent from the inner end of the wash-pan, treating it to separate out the crystalline matter held in solution therein, and return the recovered solvent to the outer end of the wash-pan for recirculation therethrough, and means for spraying with fresh crystal solvent the coated sheet after it leaves the circulating body of crystal solvent at the outer end of the wash-pan and in manner to add sprayed solvent to said circulating body of solvent.
8. Apparatus for removing from the coating of a continuous sheet crystalline matter contained therein, comprising an enclosed chamber divided from inner to outer end into a plurality of transverse compartments by double-walled partitions closed at the top and of progressively greater height, steam coils located between the walls of the compartments, means for introducing fluid crystal solvent into the outer end and for withdrawing the same from the inner end of the chamber to thereby successively fill and thereafter cause a continuous flow of a body of the solvent through the several compartments thereof, and means for effecting the travel of the coated sheet first downwardly and then upwardly through said compartments successively and in a direction opposite to that of the flow of the fluid crystal solvent.
9. Apparatus for removing from the coating of a continuous sheet crystalline matter contained therein, comprising an enclosed chamber divided from inner to outer end into a plurality of transverse compartments by double-walled partitions closed at the top and of progressively greater height, steam coils located between the walls of the compartments, means for introducing fluid crystal solvent into the outer end and for withdrawing the same from the inner end of the chamber to thereby successively fill and thereafter cause a continuous flow of a body of the solvent through the several compartments thereof, means for effecting the travel of the coated sheet first downwardly and then upwardly through said compartments successively and in a direction opposite to that of the flow of the fluid crystal solvent.
10. Apparatus for removing from the coating of a continuous sheet crystalline matter contained therein, comprising an enclosed wash-pan divided from inner to outer end into a plurality of transverse compartments by double-walled partitions closed at the top and of progressively greater height, steam coils located between the walls of the compartments, means for effecting a continuous circulation of a body of fluid crystal solvent through the several compartments of the wash-pan from its outer to its inner end including means for treating the used solvent withdrawn from the inner end of the wash-pan to separate out the crystalline matter held in solution therein and returning the recovered solvent to the outer end of the wash-pan for re-circulation therethrough, and means for effecting the travel of the coated sheet first downwardly and then upwardly through each of the successive compartments in a direction opposite to that of the flow of the fluid crystal solvent.
11. Apparatus for removing from the coating of a continuous sheet crystalline matter contained therein, comprising an enclosed wash-pan divided from inner to outer end into a plurality of transverse compartments by double-walled partitions closed at the top and of progressively greater height, steam coils located between the walls of the compartments, means for effecting a continuous circulation of a body of fluid crystal solvent through the several compartments of the wash-pan from its outer to its inner end including means for treating the used solvent withdrawn from the inner end of the wash-pan to separate out the crystalline matter held in solution therein and returning the recovered solvent to the outer end of the wash-pan for re-circulation therethrough, means for effecting the travel of the coated sheet first downwardly and then upwardly through each of the successive compartments in a direction opposite to that of the flow of the fluid crystal solvent and for spraying with fresh crystal solvent and for wiping the sheet after it leaves the circulating body of solvent and in manner to add sprayed solvent to said circulating body of solvent.
12. Apparatus for removing from the coating of a continuous sheet crystalline matter contained therein, comprising an enclosed wash-pan divided from inner to outer end into a plurality of transverse compartments by double-walled partitions closed at the top and of progressively greater height, heating means located within the walls of the partitions, means for effecting a continuous flow of a fluid crystal solvent through the several compartments of the wash-pan including means for withdrawing the used solvent from the inner end of the wash-pan and after treating it to separate out the crystalline matter held in solution therein returning the recovered solvent to the outer end of the wash-pan for re-circulation therethrough, means for causing the coated sheet to travel first downwardly and then upwardly through said compartments successively and in a direction opposite to that of the flow of said solvent therethrough, and means for spraying the

- sheet with fresh crystal solvent after it leaves the flowing body of solvent and in manner to add sufficient sprayed solvent to said flowing body of solvent to maintain the volume thereof.
- 5 13. Apparatus of the type described comprising a wash-pan divided from inner to outer end into a plurality of transverse compartments by transverse partitions of progressively greater height, means for introducing a fluid solvent into 10 the outer end and for withdrawing the same from the inner end of the wash-pan to thereby successively fill and thereafter cause a continuous flow of the solvent through the several compartments thereof, means for progressively heating 15 the solvent as it flows through said compartments successively, a cover for the wash-pan, and means mounted on the cover for carrying a continuous sheet first downwardly and then upwardly through each compartment of the wash-pan in succession and in a direction opposite to that of the flow of the solvent.
14. Apparatus of the type described comprising a wash-pan divided from inner to outer end into a plurality of transverse compartments by trans- 20 verse partitions of progressively greater height, means for introducing a fluid solvent into the outer end and for withdrawing the same from the inner end of the wash-pan to thereby successively fill and thereafter cause a continuous flow of the solvent through the several compartments thereof, means for progressively heating the solvent as it flows through said compartments successively, means for treating the solvent after leaving the inner end of the wash-pan to remove therefrom 25 the material dissolved from a sheet while flowing through the compartments of the wash-pan and thereafter re-introducing it into the outer end of the wash-pan to re-circulate therethrough, and means for wiping, means for spraying with 30 fresh fluid solvent, and means for rewiping the sheet located above and draining into the outermost compartment of the wash-pan.
15. Apparatus of the type described comprising a wash-pan divided from inner to outer end into a plurality of compartments by transverse 35 partitions of progressively greater height, means for introducing a supply of fluid solvent into the outer end and for withdrawing the same from the inner end of the wash-pan to thereby successively fill and thereafter cause a flow of the solvent through the several compartments thereof, means for progressively heating the solvent as it flows through said compartments successively, means for treating the solvent after leaving the 40 inner end of the wash-pan to remove therefrom the material dissolved from a sheet while flowing through the compartments of the wash-pan and thereafter re-introducing it into the outer end of the wash-pan to re-circulate therethrough, and means for wiping, means for spraying with 45 fresh liquid solvent and means for rewiping the sheet located above and draining into the outermost compartment of the wash-pan, and means for drying and deodorizing the sprayed and re- 50 wiped sheet.
16. Apparatus of the type described comprising a wash-pan divided from inner to outer end into a plurality of compartments by transverse partitions of progressively greater height, means for introducing a supply of fluid solvent into the outer end and for withdrawing the same from the inner end of the wash-pan to thereby successively fill and thereafter cause a continuous flow of the solvent through the several compartments thereof, means for progressively heating the solvent as it flows through said compartments successively, means for treating the solvent after leaving the inner end of the wash-pan to remove therefrom the material dissolved from a sheet while flowing through the compartments of the wash-pan and thereafter re-introducing it into the outer end of the wash-pan to re-circulate therethrough, and means for wiping, means for spraying with fresh fluid solvent, and means for rewiping the sheet located above and draining into the outermost compartment of the wash-pan.
17. Apparatus of the type described comprising a wash-pan divided from inner to outer end into a plurality of compartments by transverse partitions of progressively greater height, means for introducing a supply of fluid solvent into the outer end and for withdrawing the same from the inner end of the wash-pan to thereby successively fill and thereafter cause a flow of the solvent through the several compartments thereof, means for progressively heating the solvent as it flows through said compartments successively, means for treating the solvent after leaving the inner end of the wash-pan to remove therefrom the material dissolved from a sheet while flowing through the compartments of the wash-pan and thereafter re-introducing it into the outer end of the wash-pan to re-circulate therethrough, and means for wiping, means for spraying with fresh liquid solvent and means for rewiping the sheet located above and draining into the outermost compartment of the wash-pan, and means for drying and deodorizing the sprayed and re-wiped sheet.

GEORGE C. BORDEN, JR.
